[57] CLAIM

The ornamental design for a jogger's belt, substantially as shown and described.

DESCRIPTION

FIG. 1 is a front elevational view of a jogger's belt showing our new design;

FIG. 2 is a top plan view thereof;

FIG. 3 is a front elevational view of the water bottle holder shown separated from the belt for convenience of illustration only;

FIG. 4 is a rear elevational view thereof;

FIG. 5 is a front elevational view of the belt with the water bottle holder removed and pockets opened, and FIG. 6 is a rear elevational view of the belt shown in FIG. 1 with the water bottle holder removed for convenience of illustration. The dashed lines shown throughout the various figures represent stitching.
